PORTABLE ELECTRIC CHORD PLAYING
MECHANISM FOR PIANOS

Lee L. Von Gunten, Kenmore, N.Y., assignor to Aurora
Corporation of Illinois, Buffalo, N.Y., a corporation
of Illinois

Filed Sept. 12, 1960, Ser. No. 62,102

Term of patent 14 years

(Cl. D56—1)

FIG. 1 is a top plan view of a portable electric chord playing mechanism for pianos embodying my new design;

FIG. 2 is a front elevational view thereof; and

FIG. 3 is a side elevational view thereof.

The broken line showing of a portion of a piano keyboard is for illustrative purposes only.

The side not shown is substantially the same in appearance as the side shown and the back is plain and unornamental.

I claim:

The ornamental design for a portable electric chord playing mechanism for pianos, substantially as shown and described.
